CLAIM

The ornamental design for an ophthalmic lens, as shown and described.

DESCRIPTION

FIG. 1 is a top plan view of the ophthalmic d-lens in accordance with the present invention;

FIG. 2 is a bottom plan view of the ophthalmic lens of FIG. 1;

FIG. 3 is a left side view of the ophthalmic lens of FIG. 1; FIG. 4 is a right side view of the ophthalmic lens of FIG. 1; FIG. 5 is a front view of the ophthalmic lens of FIG. 1; and, FIG. 6 is a back view of the ophthalmic lens of FIG. 1.

The broken lines immediately adjacent to shaded areas represent the bounds of the claimed design while all other broken lines are directed to portions of the ophthalmic lens that are not claimed; the broken lines form no part of the claimed design.

1 Claim, 6 Drawing Sheets
